CLAIM

The ornamental design for a cabinet, as shown and described.

DESCRIPTION

FIG. 1 is an isometric view of a cabinet showing our new design;

FIG. 2 is a front elevational view;

FIG. 3 is a right side elevational view, the left side being a mirror image thereof;

FIG. 4 is a top plan view;

FIG. 5 is a back elevational view;

FIG. 6 is a bottom view; and

FIG. 7 is a front perspective view of a modified form of our design wherein the cabinet is narrower but otherwise identical to the cabinet of FIG. 1.
